UNITED STATES PATENT OFFICE

PAUL PATERAS PESCARA, OF PARIS, FRANCE

AIR COMPRESSOR

Application filed March 24, 1927, Serial No. 177,939, and in France April 2, 1926.

My invention relates to air compressors of the type in which two pistons are utilized which act alternately as driving pistons and compressing pistons provided with means for synchronizing the movement between said pistons, which pistons move in separate cylinders in opposite directions and which means utilizes very little of the energy transmitted to said pistons for bringing about the necessary kinematic transformation between said pistons.

The general object of my invention is, principally to improve the disposition of the various parts of the apparatus, above mentioned, and render them much safer in operation than heretofore.

Briefly outlined, the invention consists in constructing the driving pistons and compressing pistons of a single piece, thus doing away with all the usual interconnecting parts, such as cranks or piston rods, as well as the necessity of any synchronizing mechanism between the driving and compressing pistons. Said pistons are provided with cylinders having bores of different diameters and are at least as long as their length of stroke. The synchronizing parts of the coupling mechanism of the two pistons are advantageously attached to the annular faces of the two pistons and at the same time, if desired may effect the compressing stroke of one of the compressing pistons.

The compressing pistons may be disposed advantageously on the inside of the motor pistons at which time the bore of the driving pistons is made larger than that of the compressing pistons. In the latter case the synchronizing mechanism is coupled to the pistons by means of arms attached thereto and extending through longitudinally extending openings in the heads of the driving piston cylinder conveniently disposed. The coupling mechanism is established in such a manner as to contribute to the safety of the compressor by opposing the tendency of the pistons to blow out the cylinder heads, so that in case one of said pistons receives an excessive amount of kinematic energy or that one of said pistons cannot transform said energy into work due to its corresponding valves not

being properly seated, said coupling mechanism may act to transfer a part of the driving energy to the other piston from that which is unable to transform its energy into work in its corresponding compressing cylinder. 55

The invention consists further in providing said coupling mechanism with a plurality of pinions or levers oscillating through an angle of at least 360° by the movement of said pistons and utilizing said pinions or levers for performing various functions in the compressor. 60

Another object of the invention is to provide a means for circulating water through said coupling mechanism and pistons which serves not only as a cooling medium for the compressor but also as a means for regulating the weight of said pistons. 65

Other objects of the invention will be obvious to those skilled in the art in the following specification taken in connection with the accompanying drawing in which—

Fig. 1 is a diagrammatic representation showing the coupling mechanism;

Fig. 2 is a similar view showing a modified form of coupling mechanism;

Fig. 3 is a sectional elevation of a compressor constructed in accordance with the present invention, illustrating the disposition of the various parts and the water-cooling 80 arrangement;

Fig. 4 is a piston detail;

Fig. 5 is a detail of an orifice drawn to a large scale;

Fig. 6 is an elevational view with certain parts in section showing certain modifications;

Fig. 7 is a view of an ignition mechanism operated by the coupling mechanism of the pistons;

Fig. 8 is a view of a modified compressor in elevation in which the driving cylinder bore is made larger than that of the compressing cylinder;

Fig. 9 is a sectional view corresponding to Fig. 8;

Fig. 10 is an elevation of a modification of the mechanism illustrated in Fig. 8; and

Fig. 11 is a sectional view corresponding to Fig. 10. 100

Referring to the drawing, and particularly Fig. 1, the main elements of the compressor comprise a motor cylinder 15 and two larger cylinders 16 and 17 in which compression takes place. The bores of all three cylinders are arranged in axial alignment and cylinder 15 opens into cylinders 16 and 17 respectively at each end. The pistons for said cylinders are cast in a single piece and comprise portions 20, 21 fitted in compressing cylinders 16 and 17 respectively and portions 18, 19 sliding in motor cylinder 15. The portions 18, 19 are made as long as the length of stroke of their respective pistons at least for obvious reasons. One of the advantages derived from such a construction is the strengthening of the pistons and hence a smoother action of the pistons when working under load due to the increase in weight.

The mechanism for coupling the two pistons together is disclosed and claimed in my co-pending application Serial No. 177,938 filed March 24, 1927, in Figures 3 and 4 of said application. This mechanism comprises a double mechanical arrangement only half of which is here visible in Fig. 1. Briefly said mechanism comprises rods 22, 23 disposed in parallel relation to cylinders 15, 16 and 17 and which are attached respectively to pistons 18, 20 and 19, 21, by any convenient means at 24, 25 on the annular faces of said cylinders. Two guide bearings 26, 27 guide the extremities of rods 22, 23. A lever 28 comprising two arms of equal length is pivoted on a stud 29 fixed at the midpoint of cylinder 15 and extending in a direction normal to the surface thereof. Two links 30, 31 are attached at one end to rods 22, 23 respectively and at their other ends to the arms of lever 28.

The function of the mechanism thus far described will be obvious from a simple inspection of Fig. 1. It will be sufficient to state that the coupling mechanism prevents the blowing out of the heads of cylinders 16 and 17 in case their corresponding valves fail to operate as pistons 20 and 21 cannot attain the extreme ends of their respective cylinders due to the fact that at the end of their stroke cranks 30 and 31 align with lever 28 and prevent further movement of the pistons.

Referring to Fig. 2, the modified form of coupling mechanism is disclosed and claimed in my co-pending application in connection with Figs. 1 and 2, above mentioned. Here the cylinders 15, 16, 17 and pistons 18, 20 and 19, 21 are disposed in the manner described in connection with Fig. 1. Only half of the coupling mechanism is illustrated in this figure as previously. In this embodiment the rods 32, 33 are disposed parallel to the axis of cylinders 15, 16, 17 and are fixed to pistons 18, 20 and 19, 21 by any convenient means as shown at 34, 35, on the annular faces of pistons 18, 20 and 19, 21 respectively. In this embodiment, the rods are placed in the same

straight line. The extremities of rods 32, 33 slide in bearings 36, 37. A lever 38 having two arms of equal length is pivoted on a stud 39 fixed at the mid-point of cylinder 15 and extending in a direction normal to the surface thereof as explained in connection with Fig. 1. Also two cranks or links 40, 41 connect the respective ends of the rods 32, 33 and lever 38. In this embodiment also the coupling mechanism opposes the blowing out of the cylinder heads of 16, 17 by their respective pistons 18, 20 and 19, 21 in much the same manner as previously described. In this case, however, when the piston reaches the end of its stroke, the cranks 40, 41 as well as lever 38 align with rods 32, 33 bringing all these elements on the dead center point and preventing further movement of the piston toward its head.

Referring to Figs. 3, 4 and 5, a motor cylinder 42 is provided at each end with compressing cylinders 43, 44 with their axes in alignment as previously described. The arrangement of the cylinders in this case corresponds to that described in connection with Figs. 1 and 2, the compressing cylinders having the larger bore. The mechanism for cooling the compressor by means of circulating water will now be described.

Two double pistons 45, 46 are fitted to the cylinders as described in connection with Figs. 1 and 2. In this case the interior of the pistons is made hollow as shown in Fig. 4 and the interior of the pistons is divided into two compartments intercommunicating as shown at 49 by means of the partitions 47 and 48 which project into the portion of the piston having the smallest diameter.

Each piston carries a plurality of tubular members as shown at 50, 51, 52 which are disposed on the annular faces of the piston at diametrically opposite points. Members 50 and 52 of piston 45 are disposed on opposite sides of the partition 47 in such a manner that a liquid injected into piston 45 by tube 50 cannot escape through tube 52 except by flowing around said partition through orifice 49. The tubular members of piston 46 are arranged in like manner.

Each tubular member of the pistons 45, 46 is provided with a hollow rod, two of which are shown at 53, 54. Since the other two tubular members are identical and similarly disposed, the description of one pair will suffice.

The hollow rods 53, 54 are disposed parallel to the cylinders, 42, 43, 44 of the machine. Each of said rods is provided with rack teeth 55 and 56 respectively which mesh with a pinion 57 mounted on a shaft 58 carried by the midpoint of cylinder 5 and extending in a direction normal to the surface thereof.

The rod 53 terminates in a piston 59 and the longitudinally extending opening thereof extends through said piston, the orifice formed thereby being closed by an automatic

valve 60 opening in the upward direction as shown in Fig. 3.

The piston 59 is adapted to slide in a pump cylinder 61 which is integral with the frame of the apparatus and is adapted to communicate with the exterior by means of the pipe or tube 62. The orifice of pipe 62 is controlled by an automatic valve 63 opening when moved to the right. The pipe 62 communicates with the interior of cylinder 61 by means of an opening 64 of special form as clearly illustrated in Fig. 5.

The rod 54 likewise terminates in a piston 65 sliding in a pump cylinder 66 which communicates with the exterior through pipe 67. The parts just described, however, are not furnished with automatic valves or a special form of orifice as previously. The interior of rod 54 communicates freely with the outside through piston 65 pump cylinder 66 and pipe 67.

Little need be said concerning the duplicate mechanism on the opposite side of the apparatus which is not visible in the drawing. The second rod of piston 45 is mounted thereon diametrically opposite to rod 54 by means of a tubular member similar to 50. Said second rod carries a set of rack teeth similar to that carried by rod 54 and the interior thereof communicates with the exterior through a piston, a pump cylinder and pipe 68 (Fig. 3).

The same is true of the second rod mounted on piston 46 at a point diametrically opposite to member 51 by means of a coupling similar thereto. This rod is furnished with a set of rack teeth similar to that on member 53 and the interior of said rod communicates with the outside through a piston, a pump cylinder and a pipe 69 (Fig. 3). The orifice of pipe 69 is controlled by a valve in precisely the same manner as described in connection with rod 53. Similar to the visible parts, member 69 communicates to its respective pump cylinder through an opening similar to 64. The piston at the extremity of said rod is also provided with a valve as already described in connection with the visible parts.

The rods just described are all provided with packing rings as illustrated at 70, 71 where said rods enter their respective cylinders to provide a tight joint and assure efficient compression within the compression spaces 72, 73 of cylinders 43, 44 thus permitting to utilize both sides of said pistons in spite of stems 53, 54 entering said cylinders.

The apparatus just described functions in the following manner:

Suppose that piston 45 moves inwardly from the outer end of the cylinder 43, then piston 59 in combination with the valves 60 and 63 will act as a pump and cause water to be drawn in through pipe 68 through the

hollow stem of the rod corresponding to rod 54 on the opposite side (not shown) to circulate along the partition 47, pass through orifice 49 and thence through the hollow stem of 53 out through opening 64, through valve 63, which automatically opens by the force of the water, and finally into the outlet pipe 62.

When piston 46 moves inwardly precisely the same circulation of water is set up therein. A pump similar to that just described is situated opposite to rod 54 (not shown in the drawing) and draws in water through the opening 67, through the piston 65, the hollow stem of rod 54, and finally leaves the device through the outlet pipe 69.

In addition to cooling the mechanism this construction permits the mass of pistons 45 and 46 to be varied depending of course upon whether pipes 67 and 68 are connected or disconnected with a water supply.

The purpose of the special form of opening 64 is to produce a progressive reduction in cross-section between the outlet pipe and the pump cylinder and through which the water pushed back by piston 59 flows. If said pistons should move beyond the edge of orifice 64, a high resistance will be opposed to the movement thereof and hence to the movement of the whole machine. This resistance progressively slows down the pistons 45 and 46 and prevents them from blowing out the heads of compressing cylinders 43, 44, if for any reason (such as a badly seated valve for example) has allowed said pistons to pass beyond the limit of their normal stroke.

The rack teeth 55, 56 on rods 53, 54 respectively, meshing with the pinion 57, as previously described, form a convenient means for synchronizing the reciprocating motions of the pistons without an appreciable expenditure of energy during normal operation.

Referring to Fig. 6, the embodiment herein represented comprises as before, a central motor cylinder 42 and two compressing cylinders 43, 44 arranged and disposed as previously described. Pistons 72, 73 are constructed and fitted to the bores of said cylinders in a manner already described. Said pistons are provided with rods 74, 75 having rack teeth 76, 77 meshing with a pinion 78, turning on a stud 79 which is mounted on cylinder 42 the arrangement being the same as heretofore described. A duplicate mechanism of that just described is arranged symmetrically on the reverse side of the compressor and is not seen in the drawing.

In order to prevent accidental shocks between the compressing pistons and their respective cylinder heads, rods 75 and 76 carry collars 80 and 81. Between said collars and the frame of the compressor are disposed a series of "Belleville" washers 82, 83.

As previously described in connection with Fig. 3, stuffing boxes 84, 85 are provided for rods 74, 75 permitting the spaces 87, 88 to be utilized for compressing purposes.

5 The device just described functions in precisely the same manner as that described in connection with Fig. 3. The safety of the device, however, is greatly enhanced for should either compressing piston be driven 10 beyond the length of its normal stroke, its movement is opposed by the washers 82 or 83, thus preventing any shock to be transmitted between said pistons and their corresponding cylinder heads.

15 Fig. 7 illustrates a Delco ignition mechanism which may be driven by the synchronizing means of the pistons, above disclosed, and will now be described. The pinion 78 is given the proper diameter and is adapted to make 20 something less than a complete turn on its shaft 79 at each reciprocation of pistons 72, 73. The cam 86 of the ignition mechanism is adapted to be driven by pinion 78 in any convenient manner. The ignition device is of 25 a well-known type in current use and comprises a contact pawl 89 normally held in contact with a platinum contact screw 90. A secondary contact pawl 92 is provided and both contact pawls are operated by cam 86. 30 The breaking of contacts 89, 90 produces the spark for firing the motor cylinder. The arrangement is such that each piston receives a spark at the end of its stroke. The type of ignition device illustrated is well-known 35 and is used in aviation and the secondary pawl 92 permits sparks to be given only when cam 86 is turned in the direction of the arrow 91 so that the spark is given only when the pistons are in the proper end of their 40 cylinders. A casing 93 houses the mechanism and the device is supported by a lever 94 which permits the positioning of cam 86 with respect to pawl 89 and hence allows advancing or retarding of the spark.

45 It is to be understood that the ignition device might be equally used with the synchronizing mechanism disclosed in connection with Figs. 1 and 2. In this case the cam 86 would be adapted to be driven by oscillating levers 28 or 38.

50 Referring to Figs. 8 and 9 which shows the disposition of the piston synchronizing mechanism when the compressing cylinder bore is made smaller than that of the motor cylinder, a large central motor cylinder 95 is provided at each end with smaller compressing cylinders 96, 97, said cylinders being arranged in axial alignment as before. Each piston is constructed as before and comprises a compressing portion 98, 99 and a large motor portion 100, 101 said portions being fitted into cylinders 96, 97 and 95 respectively.

55 On the annular faces of pistons 98, 100 and 99, 101 are attached the rods 102, 104 and 103,

105 extending parallel to the common axis of the cylinders 95, 96, 97 and the rods 102, 103 and 104, 105 lying in the same straight line respectively.

60 Rods 102 and 104 on piston 98, 100 are attached to arms 106, 107 carried by a collar 108 slidably mounted on the outside of cylinder 96. Likewise rods 103, 105 are attached to arms 109, 110 carried by a collar 111 slidably mounted on the cylinder 97.

65 At the center of the apparatus are pivoted two levers 112, 113 each having two arms of equal length. Four connecting rods 114, 115, 116, 117 are connected at one end to the extremities of said levers and at the other end to the arms 106, 107, 109, 110 of collars 108 and 111.

70 The function of the mechanism just described is analogous to that described in connection with Figs. 1 and 2 and need not be 75 further discussed.

75 Referring to Figs. 10 and 11 which show another form of the invention in which the bore of the compressing cylinders is smaller than that of the motor cylinder, a main cylinder 118 having a constant bore through its 80 length is provided and is closed at its extremities by cover members 119, 120 which are provided with cylindrical portions 121, 122 extending into cylinder 118 but having 85 a smaller diameter than the bore thereof.

85 Two pistons 123, 124 are mounted to freely slide in cylinder 118. Each piston is provided with an annular recess which forms the compressing portions 125, 126 of each piston. 90 Said compressing portions are disposed concentrically with respect to their pistons and are adapted to freely slide within the cylindrical portions 121, 122 carried by members 119, 120. If desired, in order to utilize the 95 space occupied by the annular piston, the pistons might carry the projecting cylindrical member and project into an annular recess in the cylinder, in which case, the exterior walls of the pistons would be prolonged.

100 The cylinder 118 carries four longitudinal- 105 ly extending openings 127, 128, 129, 130 the sides of which act as bearings for the rollers 131, 132, 133, 134 mounted respectively on the arms 135 and 136, 137 and 138 fixed respectively in pairs to the pistons 123 and 124.

110 In the central part of the apparatus on one side of cylinder 118 are pivoted two levers 139, 140 and on the other side two levers 141, 142. Each lever has two arms of equal length 115 which are disposed in cross fashion with the arm of each lever on the same side.

120 On the arms 135, 136, 137, 138 of pistons 123, 124 are mounted four double armed levers 143, 144, 145, 146 the four extremities 125 of which connect with four connecting rods, the bifurcated ends 147, 148, 149, 150, 151, 152, 153, 154 of which connect with the eight 130 extremities of levers 139, 140, 141, 142.

135 The operation of the mechanism just de-

scribed is sufficiently simple as not to require explanation, being analogous to that of the synchronizing devices previously described. The particular construction just described gives an extremely compact assembly and has the advantage over the construction disclosed in connection with Figs. 8 and 9 of economizing in length a distance equal, at least, to the length of stroke of the two pistons.

Having thus described my invention what I claim as new and desire to secure by Letters Patent is—

1. In an air compressor of the type described, a plurality of compressing cylinders, a common motor cylinder therefor, said cylinders being disposed in axial alignment, a plurality of hollow pistons mounted in said cylinders, a plurality of hollow rods on each of said pistons and means for circulating cooling water through said rods and said pistons during reciprocation of the latter.

2. In an air compressor of the type described, a plurality of compressing cylinders, a common motor cylinder therefor, said cylinders being disposed in axial alignment, a plurality of hollow pistons mounted in said cylinders, a plurality of hollow rods on each of said pistons, means for circulating cooling water through said rods and said pistons during reciprocation of the latter and means interconnecting the rods on said pistons for establishing a synchronous kinematic relation between the latter.

3. In an air compressor of the type described a motor cylinder, coaxial compressing cylinders mounted at each end thereof, a piston mounted in each of said compressing cylinders having a portion extending into said motor cylinder, a plurality of rods mounted on each of said pistons and extending through said compressing cylinders, means interconnecting said rods for producing a synchronous relation between said pistons and an airtight joint between said rods and said compressing cylinders whereby said pistons may be utilized for compressing in both directions.

4. In an air compressor of the type described, a plurality of compressing cylinders, a common motor cylinder therefor, said cylinders being in axial alignment, a plurality of hollow pistons mounted in said cylinders, a plurality of hollow rods mounted on each of said pistons, means for circulating cooling water through said rods and said pistons during reciprocation of the latter and an airtight joint between said rods and said compressing cylinders whereby said pistons may be utilized for compressing in both directions.

5. In an air compressor of the type described, a plurality of compressing cylinders, a common motor cylinder therefor, said cylinders being disposed in axial alignment, a plurality of hollow pistons mounted in said

cylinders, a baffle plate dividing the interior of said pistons into two compartments, a plurality of couplings connected to each of said compartments, a plurality of hollow rods connected to said couplings, means connecting said rods for establishing a synchronous relation between said pistons and means for circulating cooling water through said rods and around said baffle plate within said pistons.

6. In an air compressor of the type described, a plurality of compressing cylinders, a common motor cylinder therefor, said cylinders being disposed in axial alignment, a plurality of hollow pistons mounted in said cylinders, a baffle plate dividing the interior of said pistons into two compartments, a plurality of couplings connected to each of said compartments, a plurality of hollow rods connected to said couplings and extending through said compressing cylinders, means connecting said rods for establishing a synchronous relation between said pistons, means for circulating cooling water through said rods and around said baffle plate within said pistons and means providing an air-tight joint between said rods and said compressing cylinders whereby said pistons may be utilized for compressing in both directions.

7. In an air compressor of the type described, a plurality of direct actuated compressing pistons mounted coaxially, compressing cylinders for said compressing pistons, a plurality of hollow rods mounted on each of said pistons, a piston mounted on each of said rods at the extremity thereof, a cylinder for each of the pistons of two of said rods having a water inlet, a cylinder for each of the pistons of the remaining rods having a water outlet, means on certain of said rods for circulating cooling water through said rods and compressing pistons and means interconnecting the rods on said pistons for establishing a synchronous kinematic relation between said compressing pistons.

8. In an air compressor of the type described, a plurality of direct actuated compressing pistons mounted coaxially, compressing cylinders for said pistons, a plurality of hollow rods mounted on each of said pistons, a piston mounted on each of said rods at the extremity thereof, a cylinder for each of the pistons of two of said rods having a water inlet, a cylinder for each of the pistons of the remaining rods having a water outlet, means on certain of said rods for circulating cooling water through said rods and compressing pistons and air-tight joints between said rods and said compressing cylinders whereby said pistons may be utilized for compressing in both directions.

9. In an air compressor of the type described, a plurality of direct actuated compressing pistons mounted coaxially, compressing cylinders for said pistons, a plural-

ity of hollow rods mounted on each of said pistons, a piston mounted on each of said rods at the extremity thereof, a cylinder for each of the pistons of two of said rods having a water inlet, a cylinder for each of the pistons of the remaining rods having a water outlet, means on certain of said rods for circulating cooling water through said rods and compressing pistons, means interconnecting the rods on said pistons for establishing a synchronous kinematic relation between said compressing pistons and means providing air-tight joints between said rods and said compressing cylinders whereby said pistons may be utilized for compressing in both directions.

10. In an air compressor of the type described, a plurality of direct actuated compressing pistons mounted coaxially, compressing cylinders for said pistons, a plurality of hollow rods mounted on each of said pistons, a piston mounted on each of said rods at the extremity thereof, a cylinder for each of the pistons of two of said rods having a water inlet, a cylinder for each of the pistons of the remaining rods having a water outlet, an automatic valve carried by each of the pistons of said last mentioned cylinders and a second automatic valve in said water outlet, said valves being so arranged and disposed that reciprocation of said compressing pistons will cause water to be circulated through the interior of said rods and said compressing pistons.

15. 11. In an air compressor of the type described, a plurality of direct actuated compressing pistons mounted coaxially, a plurality of hollow portions on the interior of said pistons, compressing cylinders for said pistons, a plurality of hollow rods mounted on each of said pistons and connecting with the interior thereof, a baffle plate on the interior of said pistons between said rods dividing the interior of said piston into two interconnecting chambers, a piston mounted on the extremity of each of said rods, a cylinder for each of the pistons of two of said rods having a water inlet, a cylinder for each piston of the remaining rods having a water outlet, an automatic valve carried by each of the pistons of said last mentioned cylinders and a second automatic valve in said water outlet, said valves being so arranged and disposed that reciprocation of said compressing pistons will cause water to be circulated around said baffle plate and through the interior of said rods and said compressing pistons.

20. 12. In an air compressor of the type described, a plurality of direct actuated compressing pistons mounted coaxially, compressing cylinders for said pistons, a plurality of hollow rods mounted on each of said pistons, a piston mounted on each of said rods at the extremity thereof, a cylinder for each of the pistons of two of said rods having a water in-

let, a cylinder for each of the pistons of the remaining rods having a water outlet, an automatic valve carried by each of the pistons of said last mentioned cylinders, a second automatic valve in said water outlet, said valves being so arranged and disposed that reciprocation of said compressing pistons will cause water to be circulated through the interior of said rods and said compressing pistons and means providing an air-tight joint between said rods and said compressing cylinders whereby said pistons may be utilized for compressing in both directions.

25. 13. In an air compressor of the type described, a plurality of direct actuated compressing pistons mounted coaxially, compressing cylinders for said pistons, a plurality of hollow rods mounted on each of said pistons, a piston mounted on each of said rods at the extremity thereof, a cylinder for each of the pistons of two of said rods having a water inlet, a cylinder for each of the pistons of the remaining rods having a water outlet, an automatic valve carried by each of the pistons of said last mentioned cylinders, a second automatic valve in said water outlet, said valves being so arranged and disposed that reciprocation of said compressing pistons will cause water to be circulated through the interior of said rods and said compressing pistons and means interconnecting the rods on said pistons for establishing a synchronous kinematic relation between said compressing pistons.

30. 14. In an air compressor of the type described, a plurality of direct actuated compressing pistons mounted coaxially, compressing cylinders for said pistons, a plurality of hollow rods mounted on each of said pistons, a piston mounted on each of said rods at the extremity thereof, a cylinder for each of the pistons of two of said rods having a water inlet, a cylinder for each of the pistons of the remaining rods having a water outlet, an automatic valve carried by each of the pistons of said last mentioned cylinders, a second automatic valve in said water outlet, said valves being so arranged and disposed that reciprocation of said compressing pistons will cause water to be circulated through the interior of said rods and said compressing pistons, means providing an air-tight joint between said rods and said compressing cylinders whereby said pistons may be utilized for compressing in both directions and means interconnecting the rods on said pistons for establishing a synchronous kinematic relation between said compressing pistons.

35. 15. In an air compressor of the type described, a plurality of direct actuated compressing pistons mounted coaxially, compressing cylinders for said pistons, a plurality of hollow rods mounted on each of said pistons, a piston mounted on each of said rods at the extremity thereof, a cylinder for each of the pistons of two of said rods having a water in-

let, a cylinder for each of the pistons of the remaining rods having a water outlet, automatic means for progressively resisting the flow of water through the water outlet, an 5 automatic valve carried by each of the pistons of said last mentioned cylinders, a second automatic valve in said water outlet, said valves being so arranged and disposed that reciprocation of said compressing pistons will 10 cause water to be circulated through the interior of said rods and said compressing pistons.

16. In an air compressor of the type described, a plurality of direct actuated compressing pistons mounted coaxially, compressing cylinders for said pistons, a plurality of hollow rods mounted on each of said pistons, a piston mounted on each of said rods at the extremity thereof, a cylinder for 20 each of the pistons of two of said rods having a water inlet, a cylinder for each of the pistons of the remaining rods having a water outlet, an automatic valve carried by each of the pistons of said last mentioned cylinders, 25 a second automatic valve in said water outlet, said valves being so arranged and disposed that reciprocation of said compressing pistons will cause water to be circulated through the interior of said rods and said compressing pistons and a tapered orifice within said outlet between said last mentioned valves for progressively limiting the movement of said last mentioned pistons toward the end of their stroke.

35 17. In an air compressor of the type described, a main driving cylinder, compressing cylinders mounted at the extremities thereof, compressing pistons mounted in said compressing cylinders having integral driving 40 pistons extending into said main cylinder, a plurality of interconnected cavities in the interior of said pistons, a plurality of pumps disposed between said compressing cylinders there being one pump for each piston and means associated with said pumps and said pistons for circulating water through said pistons.

18. In an air compressor of the type described, a main driving cylinder, compressing cylinders mounted at the extremities thereof, compressing pistons mounted in said compressing cylinders having integral driving pistons extending into said main cylinder, a plurality of interconnected cavities in 55 the interior of said pistons, a plurality of pumps disposed between said compressing cylinders there being one pump for each piston, means for driving said pumps by said pistons and means associated with said pumps and said pistons for circulating water through said pistons.

60 19. In an air compressor of the type described, a main driving cylinder, compressing cylinders mounted at the extremities thereof, compressing pistons mounted in said com-

pressing cylinders having integral driving pistons extending into said main cylinder, a plurality of interconnected cavities on the interior of said pistons, a plurality of pumps disposed between said compressing cylinders there being one pump for each piston, means 70 associated with said pumps and said pistons for circulating water through said pistons and cushioning means associated with said pumps for retarding the motion of said compressing pistons when approaching one end of their stroke.

20. In an air compressor of the type described, a main driving cylinder, compressing cylinders mounted at the extremities thereof, compressing pistons mounted in said compressing cylinders having integral driving pistons extending into said main cylinder, a plurality of interconnected cavities on the interior of said pistons, a plurality of pumps disposed between said compressing cylinders there being one pump for each piston, means 80 associated with said pumps and said pistons for circulating water through said pistons, cushioning means associated with said pumps for retarding the motion of said compressing pistons when approaching one end of their stroke and means interconnecting said pumps for synchronizing said compressing pistons. 85

21. In an air compressor of the type described, a main driving cylinder, compressing cylinders mounted at the extremities thereof, compressing pistons mounted in said compressing cylinders having integral driving pistons extending into said main cylinder, a plurality of interconnected cavities on the interior of said pistons, a plurality of pumps disposed between said compressing cylinders there being one pump for each piston, means 100 associated with said pumps and said pistons for circulating water through said pistons, cushioning means associated with said pumps for retarding the motion of said compressing pistons when approaching one end of their stroke, a plurality of racks carried by said pumps and a pinion meshing with said racks whereby synchronous movement between said compressing pistons is assured. 105

22. In an air compressor of the type described a plurality of direct actuated compressing pistons mounted coaxially, compressing cylinders for said pistons, a plurality of hollow rods mounted on each of said pistons, a piston mounted on each of said rods at the extremity thereof, a cylinder for each of the pistons of two of said rods having a water inlet, a cylinder for each of the pistons of the remaining rods having a water outlet 120 and means on certain of said rods for circulating cooling water through said rods and said compressing pistons. 125
